OSCILLATOR CIRCUITS

Jeffrey S. Cohen, Los Angeles, Calif., assignor to
Avco Manufacturing Corporation, Cincinnati,
Ohio, a corporation of Delaware

Application June 25, 1947, Serial No. 756,991

9 Claims. (Cl. 250—36)

1

The present invention relates to alternating current electrical generators, particularly to electromagnetic wave signal generators, and, it has a wide range of prospective application, specifically to a tunable local oscillator particularly suitable for incorporation in superheterodyne receivers of the type adapted for frequency modulation (or ultra high frequency), short-wave or standard broadcast signal reception.

The superheterodyne receiver includes a local oscillator, the function of which is to generate oscillations which are beat against the received carrier-wave signals to produce difference-frequency signals. For example, when receiving 540 kilocycle standard broadcast carrier signals an oscillator operating at 6365 kilocycles may be employed, in conjunction with a mixer, to develop intermediate frequency signals having a frequency of, say, 5825 kilocycles. Since the standard broadcast band extends to 1600 kilocycles, the local oscillator should be tunable between 6365 and 7425 kilocycles, for broadcast reception.

When receiving 9.45 megacycle short-wave carrier signals an oscillator operating at 15.275 megacycles may be used, for example. For a short-wave band extending to 11.9 megacycles, the oscillator should be tunable between 15.275 and 17.725 megacycles, when the same intermediate frequency of 5.825 megacycles is required.

When receiving 88.1 megacycle frequency modulated signals, for example, a local oscillator operating at 98.8 megacycles may be used, assuming an intermediate frequency of 10.7 megacycles. This oscillator should be tunable between 98.8 megacycles and 118.6 megacycles, for a frequency modulation band extending to 107.9 megacycles.

The above mentioned parameters are illustrative but they show that in a three-band receiver having such parameters three oscillator frequency range requirements must be met:

First, a variable source of local oscillations within the frequency range 6365 to 7425 kilocycles is required, for broadcast (BC) operation;

Second, a variable source of local oscillations within the frequency range 15.275 and 17.725 megacycles is required for short wave (SW) operation;

Third, a variable source of local oscillations within the frequency range 98.8 to 118.6 megacycles is required, for frequency modulation (FM) signal reception.

In effect, a three-band receiver requires three local oscillation generating systems. It will be seen that, in substance, three different oscillator

circuits are required. It is desirable to employ a common electronic oscillator tube for these three systems. The objective of quality radio receiver-manufacturers is to furnish the "most radio with the least number of components and tubes," minimizing costs to the consumer and service troubles. When employing a common tube, the various frequency-determining circuit elements, such as inductances and capacitances, have heretofore had to be wholly mechanically switched in and out of circuit association with that tube in order to obtain the required three types of operation. It is also desirable to employ the same tuning condenser during the three types of operation and fully to utilize common circuit elements wherever possible. These and other requirements, however, have created a dilemma which the radio industry has heretofore tried in vain to solve, in that mechanical switch contacts have heretofore been introduced in the FM or U. H. F. frequency-determining and oscillator circuits when the desired objectives were sought. It is urgent from a standpoint of stability and reliability of performance that, when the oscillator is switched into FM or U. H. F. operation, no current-carrying or "hot" switch contacts be included in its circuit.

An oscillator for FM or U. H. F. receivers is an extremely sensitive and critical device and extraneous factors, particularly switch contacts, impair its stability. It is essential that, once the receiver is tuned for the reception of signals from a given station the generated frequency of the oscillations be as nearly constant as possible. Various factors tend to cause that frequency to change: aging, variation of inductance and capacitance with temperature, variations in the interelectrode capacity of the oscillator tube as a result of change in temperature or tube replacement, variations in the load reactance coupled into the oscillator, variations in supply voltage, and so on. By careful design the effects of many of these undesired factors may be minimized. However, frequency stability is so adversely and drastically affected by the presence of switch contacts in the FM or U. H. F. oscillator circuits that it has heretofore been considered necessary to employ a separate and distinct oscillator tube for proper FM operation, rather than to switch circuit components into and out of electrical association with a common tube. Such switch contacts cause very serious variations in the resistance, capacitance and inductance of the frequency-determining or tank cir-

cuit of the FM or U. H. F. oscillator and upset its stability.

It is, accordingly, the principal object of the invention to provide a simple means for adjusting a common oscillator tube from low (SW or BC) to high (U. H. F. or FM) frequency operation without including current-carrying switch contacts in its frequency-determining circuits during FM or U. H. F. operation.

Another basic object of the invention is to provide an oscillator circuit, suitable for the above-mentioned two or more types of operation, and having a single tube or tube section and a minimum number of parts or circuit elements.

A further important object of the invention is to provide such an oscillator circuit, so arranged that the same tuning capacitor may be employed during the two or more types of reception.

Other and further objects and capabilities of the invention will be apparent from the following description of the accompanying drawings in which there are illustrated two preferred embodiments of multi-purpose oscillators in accordance with the invention.

In the drawings, Fig. 1 is a diagram showing the active circuit components of an illustrative oscillator circuit in accordance with the invention during the U. H. F. or FM operation; Fig. 2 is an electrical equivalent diagram of the Fig. 1 circuit; Fig. 3 shows the circuit components during BC operation; Figs. 4, 5, and 6 are simplified electrical equivalent diagrams of the Fig. 3 circuit; Fig. 7 shows the circuit components during SW operation; Fig. 8 is a simplified electrical equivalent diagram of the Fig. 7 circuit; Fig. 9 is a diagram showing all the circuits of a commercially successful form of three-purpose oscillator in accordance with the invention; Fig. 10 is a sectional view showing the U. H. F. tank circuit inductance and certain associated capacitors included in either embodiment; and Fig. 11 is a simplified form of dual-purpose oscillator circuit in accordance with the invention.

Referring now first to Fig. 10, there is provided a U. H. F. tank-circuit inductance 12, formed as a single metallic loop. It may be silverplated to minimize R. F. losses. The terminals of this loop are conductively secured to the separate stator portions 13 and 14 of a split-stator tuning capacitor or variable condenser 15. The rotor portions 16 and 17 of this condenser are mounted on a common grounded shaft 18. Bridged across the loop is a capacitor 21, having its plates 19 and 20 individually conductively connected to the legs of the loop. The inductance of inductance 12 and the parallel capacitance including that of units 21 and 29 are such that at the U. H. F. range, such as 118.6 megacycles, for example, a high parallel-resonant circuit impedance exists between points X and Y, that is, between the loop terminals and between stator portions 13 and 14. It will be seen that inductance 12 and the portions 15a and 15b of condenser 15 are then equivalent to an inductance in parallel with a series combination of two capacitors 15a and 15b, i. e. to the tank circuit of a Colpitts oscillator. This tank circuit is tunable by rotation of shaft 18. Rotor 18 of condenser 15 is grounded.

On the other hand, when the generated oscillations are on the order of 6365 to 7425 kilocycles, say, for BC operation, or 15.275 to 17.725 megacycles, say, for SW operation, the impedance of the theretofore anti-resonant circuit includ-

ing inductance 12 decreases to such an extent that stator portions 13 and 14 are effectively connected to each other, inductance 12 then being a virtual short circuit and capacitors 21 and 29 being shorted out. The circuit elements 12, 21, 29 and 15a and 15b then become equivalent to a variable condenser, portions 15a, 15b being in parallel, with the common rotor terminal P grounded and the other terminal Q common to both stator portions. Without any mechanical switching whatever, in the Fig. 10 or Fig. 1 tank circuit elements, then, that which is effectively a capacitance during BC and SW operation, becomes a Colpitts tank circuit during the U. H. F. or FM operation. Conversely, that which is a Colpitts tank circuit during U. H. F. or FM operation, effectively becomes a capacitance during BC or SW operation. With this key in mind, the detailed description of the circuits proceeds.

The capabilities of a parallel combination of inductance and capacitance (i. e., to act like a very high impedance or resonant circuit at U. H. F. frequencies, but like a short circuit at lower BC or SW frequencies) are here utilized. Such a combination is a frequency-responsive non-mechanical switch.

Referring now specifically to Fig. 1, there is shown a Colpitts capacitive feedback oscillator particularly suitable for U. H. F. operation. It comprises an oscillator tube 23, employing a shunt-fed plate-supply voltage, the anode being connected to a suitable source of space current through a resistor 24 or the like. The grid resistor 25 is effectively connected between grid and ground, since it is connected to a center tap on loop 12, through the upper portion 26 of an inductance 27. An iron core 28 is provided for the inductance 12. Capacitor 24 projects through and is snugly mounted in openings in the legs 30 and 35 of loop 12. In addition to capacitor 24, the plates of which are individually soldered to the terminals of loop 12, there may be provided a trimmer capacitor 29, in parallel with capacitor 24. The tank circuit comprises inductance 12, the split-stator condenser 15 (equivalent to two ganged variable condensers 15a and 15b in series), with their junction grounded, and the parallel combination of capacitors 21 and 29. Tuning is accomplished by turning rotor shaft 30 18 of ganged condensers 15a and 15b. The tank circuit terminals are connected to the plate and grid of tube 23, the plate connection being made through series blocking capacitors 31 and 32. The purpose of capacitor 31 is hereinafter explained in more detail. Capacitors 53 and 54 are provided for oscillator coupling purposes. For U. H. F. it was found preferable to couple from the grid side of the oscillator, and capacitor 53 serves to couple the oscillator voltage to the 50 converter tube. Capacitor 54 is open circuit on U. H. F.

As clearly shown in Fig. 9, wipers 33 and 34 are in position F during U. H. F. or FM operation, so that all circuit components (other than 55 those shown in Fig. 1) are entirely disconnected from the oscillator circuit. No current-carrying switch contacts whatever are then in the U. H. F. oscillator circuit. The point of interconnection Q of inductance 12 and inductance 27 is at ground potential for U. H. F. signals, and that inductance 27 in no way affects the U. H. F. oscillations. Further, since wiper 33 (Fig. 9) is in position F, inductance 27 is open circuited. It will be seen, then, from the electrical equivalent 70 circuit shown in Fig. 2 that the oscillator func-

tions as a conventional Colpitts circuit during U. H. F. operation, loop 12 then being the tank circuit inductor.

BC operation is next considered.

Wipers 34 and 33 are ganged, as by any suitable expedient indicated, by the dashed line 37 (Fig. 9). As stated above, during BC or SW operation, inductor 12 and capacitors 29, 15 and 21 are equivalent to a variable condenser (15a, 15b in parallel), having one common terminal P grounded. The other common terminal Q is connected to the center tap of inductance 27. All parts of the cross-hatched area in Fig. 3 are then at the same R. F. potential as indicated in the description of Fig. 10. Both parallel parts of condenser 15 now function as one of the tank circuit capacitances. It will be recalled that a Colpitts oscillator tank circuit requires an inductance and two series capacitors, forming a resonant circuit. Inductance 27 is the required inductance. Capacitors 36-35 comprise the other required tank circuit capacitance. Inductance 27 functions as the tank circuit inductance. To switch in said other tank circuit capacitance, wiper 33 is placed as shown in position B, connecting the ungrounded terminal of the parallel combination of capacitors 35, 36 to the remaining terminal of inductance 27. The junction of inductance 27 and condenser 15 is already connected to the grid. But inductance 27 must be placed across the grid and plate of tube 23. To couple the junction of inductance 27 and condensers 36, 35 to the plate, wiper 34 is placed as shown in position B, whereby that junction is connected to the junction of capacitors 31, 32. Capacitor 32 now functions as a blocking condenser and capacitor 31 is in parallel with the tank circuit inductance 27. Oscillator voltage is now delivered to the convertor tube through coupling condenser 54, condenser 53 being open circuit. In addition, oscillator plate voltage is reduced by removing the short circuit from resistor 24A and thus placing resistors 24 and 24A in series.

Figs. 3, 4, 5, and 6 show progressive circuit equivalents for the BC oscillator circuits. In Fig. 4 the wipers 33, 34 are deleted, grid resistor 25 is transposed and capacitors 35, 36 are combined. In Fig. 5, capacitor 31 is placed in an equivalent electrical location and capacitors 16 and 17 are combined. In Fig. 6, the parts are rearranged, in order to show graphically that the net result of the positioning of wipers 33 and 34 is to produce a simple Colpitts oscillator circuit, with inductance 27 and capacitors 31, 35, 36 and both parallel parts of condenser 15 as its tank circuit.

For SW operation wipers 33 and 34 are placed in the S position (Fig. 9). An inspection of Figs. 7 and 8 will show that a simple Colpitts oscillator is again produced with portion 26 only of inductance 27, and capacitors 31, 38 and both parallel parts of condenser 15 as its tank circuit. One terminal of inductance 26 is already effectively connected to the ungrounded terminal Q of condenser 15. Wiper 33 connects the other terminal of inductance 26 to the ungrounded terminal of a capacitor 38 and their junction point is connected by wiper 34 to the junction of condensers 31, 32 in order to place the tank circuit across the grid and plate of tube 23. The essential difference between the SW and BC circuits is that during SW operation inductance portion 26 and condenser 38 are substituted for inductance 27 and condensers 35, 36 respectively.

The ungrounded junction of capacitors 36, 35

is connected to terminals 40 and 46. The ungrounded terminal of capacitor 38 is connected to terminals 41 and 47. The terminal of inductance 27 remote from point Q on coil 12 is connected to terminal 48. The tap terminating inductance portion 26 is connected to terminal 49. The junction of condensers 31, 32 is connected to spaced terminals 43, 44. During BC operation wiper 34 connects terminals 40 and 43 and wiper 33 connects terminals 46 and 48. During SW operation wiper 34 connects terminals 41 and 44 and wiper 33 connects terminals 47 and 49.

During FM operation condensers 36, 35, 38, wipers 33 and 34 and terminals 46, 47, 40 and 41 have no operative effects on the oscillator.

Explanation of the construction and operation of a Colpitts oscillator per se is not herein required, since such oscillator is well known to the art and described for example, in: Applied Electronics, M. I. T. Staff, page 617 et seq., Wiley, New York, 1943; Radio Engineering, Terman, page 349 et seq., McGraw-Hill, New York, 1937; Theory and Applications of Electron Tubes, Reich, page 391 et seq., McGraw-Hill, New York, 1944.

In one successful commercial embodiment of the invention operating on the above mentioned frequencies the following illustrative circuit parameters were found to be suitable:

30 Capacitor 32—91 mmf., 300 volts, ceramic
Capacitor 31—39 mmf., 300 volts, ceramic
Resistor 25—22,000 ohms, 1/2 watt
Condenser 15—Two variable sections, each 57 mmf. max.
35 Capacitor 21—50 mmf., 500 volts, ceramic
Resistor 24—10,000 ohms—1 watt
Resistor 24A—120,000 ohms, 1 watt
Capacitor 29—3-30 mmf., air trimmer
Capacitor 38—3-30 mmf., air trimmer
40 Capacitor 36—3-30 mmf., air trimmer
Capacitor 35—10 mmf., 300 volts, ceramic
Tube 23—Section of Type 7F8 Triode
Inductance 12—Strap, $\frac{7}{16}$ " wide, 1" dia., silver plated
45 Inductance 27—Coil 39 $\frac{1}{4}$ turns on .375 O. D. inch form, #30 B & S ga. enameled copper wire, wound 52 turns per inch.

50 During BC and SW operation, condenser 15 is used as a single-ended capacity. The condenser 15 is used for tuning the oscillator during all three types of operation. Only one oscillator tube is used. No switch contacts are present in the U. H. F. frequency-determining circuit. While the Fig. 9 circuit is simple and inexpensive, it overcomes the disadvantages and limitations of prior art circuits.

Referring now to Fig. 11, wherein a very simple form of the invention is shown, it will be seen that elements 23, 12, 29, 21, 15a, 15b and 32 comprise the U. H. F. oscillator. A parallel combination of inductance 27 and capacitance 31 is interposed between any ungrounded part of the U. H. F. resonant circuit 12, 29, 21, 15a, 15b and either the anode or grid of tube 23. In the illustrated form shown, the combination is interposed between the anode (which is blocked for D. C. by capacitor 32) and the junction of coil 12 and capacitor 15b. The parameters of elements 27 and 31 may be made such that the U. H. F. operation is not appreciably affected by their presence. When BC operation is desired, for example, capacitor 35, 36 is connected between ground and 75 the junction of inductance 27 and capacitor 32.

(If the abovementioned 27, 31 combination is interposed in the grid lead, then the capacitor 35, 36 is connected between ground and grid.) During BC operation the tank circuit comprises inductance 27, capacitors 31, 15a, 15b and 36, 35. In one aspect, then, the invention comprises a U. H. F. Colpitts oscillator having an electron tube, a U. H. F. L-C tank circuit, a parallel combination of an inductance and capacitor interposed between either the grid or plate of the tube and said tank circuit, a capacitor, and means for shunting said capacitor across the corresponding one of either the grid or plate circuits of the tube, the parameters of said inductance and capacitance being such that, together with the variable condenser elements in said L-C tank circuit, they function as a lower-frequency Colpitts oscillator circuit.

While there has been described what is at present considered the preferred embodiment of the present invention, it will now be obvious to those skilled in the art—who have the disclosure before them—that various modifications and substitutions of equivalents can be made without departing from the true scope of the invention. It is, accordingly, intended in the appended claims to cover all such changes and modifications as fall within the true scope of the invention. For example, it is obvious to those skilled in the art that the tube leads could be reversed at points 50, 51 (Fig. 9). That is, the terminal of plate condenser 32 remote from the anode could be connected to the junction of coil 12 and condenser 15a, and the terminal of condenser 31 remote from loop 12, together with contacts 44, 43, could be connected to the grid of the tube 23. In that case, resistor 25 would be connected directly to the grid. Further, while the Colpitts type of oscillator was chosen for purposes of illustration, the invention is not limited to that particular type. Also, it will be obvious that separate coils could be used for SW and BC in place of the tapped coil 27.

Having thus described my invention, I claim:

1. In combination, an oscillator tube, a parallel circuit between its anode and control electrode comprising an inductance adapted to function as a short circuit at standard AM broadcast frequencies, and including a pair of series-connected capacitors bridged across said inductance with their junction effectively connected to the cathode whereby said inductance and said capacitors are adapted to function as an oscillator tank circuit at ultra-high frequencies but as a pair of parallel capacitors at AM broadcast frequencies, another inductance having a terminal connected to the first-named inductance, a pair of capacitors interposed between the anode of said tube and said parallel circuit, a fifth capacitor having a terminal effectively connected to the cathode of said tube, switching means for simultaneously connecting the remaining terminal of said other inductance to the remaining terminal of said fifth capacitor and to the junction of the last-mentioned pair of capacitors, said other inductance and said fifth capacitor and said parallel capacitors having such parameters that they are adapted to function as an oscillator tank circuit at frequencies within the range whereat the first-mentioned inductance functions as a short circuit.

2. A dual purpose oscillator for upper band and AM broadcast operation, having no mechanical switch contacts among its upper band frequency-determining elements comprising: An electronic

5 tube having a D. C. blocked anode, a series combination of an inductance and a blocking capacitor bridged across the anode and control electrode of said tube, a pair of series-connected capacitors bridged across said inductance, said series-connected capacitors having a junction effectively connected to the cathode of said tube, another inductance having a terminal connected to the first-named inductance, another capacitor having a terminal effectively connected to said cathode, and circuit-making-or-breaking means for connecting together the remaining terminals of said other capacitor and said other inductance and for connecting said other inductance across said anode and control electrode, said other inductance and said series-connected capacitors and said other capacitor having such parameters that they function as an oscillator tank circuit at AM broadcast frequencies while said circuit-making-or-breaking means is closed, said tuned inductance having such parameters that it acts as a short-circuit and connects said series connected capacitors in parallel at AM broadcast frequencies, said circuit-making-or-breaking means being operative to disable said other capacitor when high frequency operation is desired, the first-named inductance and said series-connected capacitors having such parameters that they function as an oscillator tank circuit for upper band reception.

3. A dual purpose oscillator in accordance with claim 1 wherein said series-connected capacitors are variable in synchronism to tune the oscillator during all above-mentioned types of operation.

4. A two-band oscillator comprising an electronic tube, an inductance between plate and grid of said tube, a pair of capacitors one of which is in circuit between plate and cathode of said tube and the other of which is in circuit between grid and cathode of said tube, said inductance and pair of capacitors being comprised in a resonant high-frequency tank circuit, a second inductance and third capacitor and means interposing them between said tank circuit and one of the cold electrodes of said tube, a fourth capacitor, and means for effectively connecting said fourth capacitor between said cold electrode and the cathode during lower-frequency operation, the said pair of capacitors being effectively connected between the other cold electrode of said tube and its cathode by said first inductance during lower-frequency operation and said first-inductance becoming a short-circuit during such operation, whereby said second inductance and said pair of capacitors and said fourth capacitor function as a tank circuit at said lower frequencies.

5. In an oscillator for two widely spaced bands, the combination comprising a vacuum tube having at least a cathode and cold anode and control electrodes, a high frequency oscillation circuit for the upper band comprising a parallel combination of a first inductance and a series-connected pair of capacitors across said inductance, said inductance being a short circuit for the low-frequency band, said capacitors each having one terminal effectively connected to said cathode, a second or low-frequency inductance having one terminal conductively connected to said first inductance, a third capacitor in series with said first inductance, means for coupling said second inductance and said third capacitor in parallel between the remaining terminals of said pair of capacitors and a cold electrode, a fourth capac-

itor, switching means for effectively connecting said fourth capacitor between said cathode and said one of said cold electrodes, said second inductance and fourth capacitor and said pair of capacitors comprising a low-frequency oscillation circuit adapted to be selected by the operation of said switching means, and means including a fifth or blocking capacitor for R. F. coupling said first inductance across said cold electrodes.

6. In an oscillator for two widely spaced bands, 10 the combination comprising a vacuum tube having at least a cathode and anode and control electrodes, a high frequency oscillation circuit for the upper band comprising a parallel combination of a first inductance and a series-connected pair of tuning capacitors across said inductance, said inductance being a short circuit for the low-frequency band, said capacitors each having one terminal effectively connected to said cathode, a second or low-frequency inductance having one terminal conductively connected to said first inductance, a third capacitor, means for coupling said second inductance and said third capacitor in parallel between the remaining terminals of said pair of capacitors and said control electrode, a fourth capacitor, switching means for effectively connecting said fourth capacitor between said cathode and said control electrode, said second inductance and fourth capacitor and said pair of tuning capacitors comprising a low-frequency oscillation circuit adapted to be selected by the operation of said switching means, and to be tuned by said pair of tuning capacitors, and means including a fifth or blocking capacitor for R. F. coupling said first inductance between said anode and control electrodes.

7. In an oscillator for an FM and short-wave two band receiver two widely spaced bands, the combination comprising a vacuum tube having at least a cathode and cold anode and control electrodes, a high frequency oscillation circuit for the upper band comprising a parallel combination of a first inductance and a series-connected pair of tuning capacitors across said first inductance, said inductance being a short circuit for the low-frequency band, and said capacitors each having one terminal effectively connected to said cathode, said inductance having such a value that during the lower-frequency reception it effectively connects said tuning capacitors in parallel between one of said cold electrodes and said cathode, means including a switch added to such tube and a second inductance and pair of capacitors for completing an oscillating circuit for the lower-frequency band, and means for permanently R. F. coupling said first inductance between said anode and control electrodes, said second inductance having one terminal permanently conductively connected to said first inductance.

8. In an oscillator for two bands, a combination which acts as an oscillator for a high frequency band and a low frequency band comprising a vacuum tube having at least a cathode and cold anode and control electrodes, a high fre-

quency oscillation circuit for the upper band comprising a parallel combination of a first inductance and a series-connected pair of gang tuning capacitors across said inductance, said capacitors each having one terminal effectively connected to said cathode, said inductance being a short circuit for the low-frequency band, whereby said capacitors are effectively connected, for lower band operation, between said cathode and one of said cold electrodes to function effectively as a tuning capacitor for the low-frequency band, means for R. F. coupling said first inductance between said anode and control electrodes, and means including a switch and a second inductance having a terminal permanently conductively connected to the first-mentioned inductance for cooperating with said tuning capacitor to function as a low frequency tank circuit.

9. A three-terminal tank circuit suitable for use in a two-band oscillator comprising a high frequency oscillation circuit for the upper band consisting of three terminals and a parallel combination of a first inductance having a high impedance at the high frequency band and a series connected pair of gang tuning capacitors across said inductance, said pair of capacitors and first inductance acting as a high frequency tank circuit, said pair of capacitors having a junction which forms one terminal, a third capacitor in series with said first inductance, one end of said first inductance and one terminal of said third capacitor forming the second and third terminals, respectively, said inductance being a short circuit for the low frequency band, whereby said pair of capacitors are effectively connected in parallel for low band operation between said first terminal and either of the other two terminals to function effectively as a tuning capacitor for the low frequency band, and means including a switch and a second inductance bridged across said third capacitor and having at least one terminal permanently conductively connected to the first-mentioned inductance for cooperating with said tuning capacitor to function as a low frequency tank circuit, the last-mentioned means also including a fourth capacitor adapted to be connected by said switch between said first terminal and the other one of said two terminals to complete a low frequency tank circuit including at least said second inductance, said pair of tuning capacitors and said fourth capacitor.
